ELECTRIC REFRIGERATOR

Robert M. Lewis, Columbus, Ga.

Application May 19, 1938, Serial No. 208,897

1 Claim. (Cl. 62—89)

The invention relates to an electric refrigerator and more especially to that class of refrigerators having a built-in hydrator.

The primary object of the invention is the provision of a refrigerator of this character, wherein there is built a hydrator separated from the cooling chamber in which is located the chilling or cooling unit so that vegetables placed within the refrigerator, that is to say, within the chamber 10 effective as a hydrator, will be kept fresh and cool without liability of having the moisture removed and thus maintaining the same crisp and in a state of natural moist condition, this being particularly true with respect to lettuce, celery, snap beans, squash, carrots, beets, citrus fruits and other products of a perishable kind, the hydrator characteristic of the refrigerator being novel in its make-up.

Another object of the invention is the provision 20 of a refrigerator of this character, wherein the hydrating compartment is readily accessible from without and is a built-in part of such refrigerator so that fruits and vegetables can be stored conveniently and maintained in their natural moist 25 state and in a fresh condition during storage of the same.

A further object of the invention is the provision 30 of a refrigerator of this character, wherein the hydrating chamber therein is insulated similarly to the insulating of the body of such refrigerator and is separated from the cooling chamber within the latter by a separator partition which allows the transferring of cooled air from such cooling chamber into the hydrating chamber 35 for maintenance of the products held therein moist and fresh, the products being properly held within said hydrating chamber to eliminate contamination and also to have the same readily accessible and to be subjected to hydrating activity 40 and without closely confining such product within closed containers.

A further object of the invention is the provision 45 of a refrigerator of this character, which is simple in its construction, thoroughly reliable and efficient for hydrating purposes and for refrigeration and inexpensive to manufacture.

With these and other objects in view, the invention consists in the features of construction, combination and arrangement of parts as will be 50 hereinafter more fully described, illustrated in the accompanying drawing, which discloses the preferred embodiment of the invention and pointed out in the claim hereunto appended.

In the accompanying drawing:

55 Figure 1 is a vertical transverse sectional view

through a refrigerator constructed in accordance with the invention.

Figure 2 is a fragmentary sectional view taken on the line 2—2 of Figure 1 looking in the direction of the arrows.

Similar reference characters indicate corresponding parts throughout the several views in the drawing.

Referring to the drawing in detail, A designates generally a refrigerator constructed in accordance 10 with the invention and comprises an outer casing 5 built interiorly thereof with a lining 6 effecting inner walling about a cooling chamber or compartment 7 and a hydrator space or chamber 8, respectively, while between such lining 6 and the 15 outer casing 5 is the usual insulating material 9 commonly employed for the insulation of refrigerator bodies of the electric type.

As is usual, within the chamber 7 is a receiver 20 10 for a cooling unit (not shown), being of the electric type, a drain 11 being extended downwardly from the enclosure 10 for the delivery of water into the chamber 8 particularly when defrosting is restored to in the use of the refrigerator while leading from the chamber 8 is a drain 12 which opens into an accessible space 13 in the 25 lowermost portion of the casing 5 and this drain relieves the chamber 8 of excessive water supply as may be delivered thereto from the drain 11 during defrosting of the refrigerator.

The compartments 7 and 8 are separated from 30 each other by means of a horizontal partition 14 which constitutes a bottom for the chamber 7 and a ceiling for the chamber 8, respectively.

As usual, the front of the refrigerator has built 35 therein a door, a portion of the same being indicated at 15, giving access to the interior of the chamber 7, which is the cooling or chilling chamber of the refrigerator.

This front of the refrigerator has built there- 40 with a door 16, which gives access to the chamber 8, while removable racked within the latter is a plurality of superposed trays or drawers 17, each having a reticulated or foraminous bottom 18 and these drawers or trays 17 are susceptible 45 of being removed from the rack mounting there- or from within the compartment 8. The reticulated or foraminous bottom 18 of the drawers or trays 17 allows drippings to pass from the uppermost of these trays or drawers to and through the lowermost thereof onto the bottom of the compartment 8 and any excess drippings will be drained off through the drain 12. The trays or drawers 17 are for accommodating products such as lettuce, celery, snap beans, squash, carrots, 50 55

beets, citrus fruits and vegetables carrying moisture, these when confined within the compartment will be maintained in a moist condition and fresh as well as properly cooled for rendering the same crisp and in a fresh condition. The chamber 8 through the construction thereof and the arrangement of the trays or drawers 17 therein effects the hydrating activity for the maintenance of stored substances or products in a naturally moist, fresh and crisp condition.

The partition 14 is devoid of insulation so that the compartment 8 will be maintained cool but at a less degree than the coolness or chill within the chamber 7 of the refrigerator and thus the said compartment 8 through condensation activity and the delivery of water from the enclosure 16 at the time of defrosting of the refrigerator will be maintained in a moist state and also for hydrating activity.

What is claimed is:

In a refrigerating apparatus, the combination of a food storage compartment, a cooling element in the food storage compartment, a partition arranged within said compartment considerably below the cooling element for dividing said compartment into upper and lower chambers, a drain tube leading from the cooling element into the lower chamber, the said lower chamber being formed with a trap at its bottom, a drain 10 leading from said trap to without the lower chamber, a plurality of superposed trays arranged in the lower chamber, removable therefrom and having reticulated bottoms and open at their tops, and means built with the refrigerating apparatus 15 for giving access to the upper and lower chambers.

ROBERT M. LEWIS.
